(57) **ABSTRACT**

Proposed is a multi-band antenna module in which antennas having different polarization characteristics are coupled so as to prevent deterioration in isolation caused by interference between the antennas. The proposed multi-band antenna module comprises a circuit board. On the top surface of the circuit board, a first upper clearance area, a second upper clearance area, an upper radiator, and an upper ground are defined so as to operate as a PIFA antenna resonating in a first frequency band. On the first upper clearance area and the second upper clearance area, a first conductor area and a second conductor area operating as a monopole antenna resonating in a second frequency band are defined.

MULTI-BAND ANTENNA MODULE**TECHNICAL FIELD**

The present disclosure relates to a multi-band antenna module, and more specifically, to a multi-band antenna module mounted on portable terminals, electronic devices constituting a home network, and the like.

BACKGROUND ART

As wireless communication technologies have recently developed, the wireless communication technologies are being applied to fields closely related to daily life, and a home network is an example.

For the home network, multi-band characteristics are required. Therefore, multi-band antenna modules for providing multi-band characteristics using multiple antennas are installed in electronic devices belonging to the home network.

However, in a multi-band antenna module composed of multiple antennas, interference occurs between antennas with the same polarization, and the interference between the antennas may cause the degradation of isolation, resulting in poor antenna performance.

Matters described above in the background art are intended to help understanding of the background of the disclosure and may include matters not related to the known related art.

SUMMARY OF INVENTION**Technical Problem**

The present disclosure has been proposed in consideration of this point and is directed to providing a multi-band antenna module in which antennas with different polarization characteristics are coupled to prevent the degradation of isolation caused by interference between the antennas.

In addition, the present disclosure is directed to providing a multi-band antenna module for enabling stable communication by coupling antennas with different polarization characteristics to increase a transmission capacity and a transmission rate through an increase in the number of channels and preventing interference between antennas in different frequency bands.

Solution to Problem

To achieve the object, a multi-band antenna module according to an embodiment of the present disclosure includes a circuit board configured by stacking a first metal layer on an upper surface of a resin layer and stacking a second metal layer on a lower surface of the resin layer, wherein a first upper clearance area formed from a first side surface of the circuit board toward a center point of the circuit board, a second upper clearance area formed in a direction from a second side surface of the circuit board in contact with the first side surface of the circuit board to the center point of the circuit board and spaced apart from the first upper clearance area, an upper radiator surrounded by the first and second side surfaces of the circuit board, the first upper clearance area, and the second upper clearance area, an upper ground surrounded by third and fourth side surfaces of the circuit board that are opposite to the first and second side surfaces of the circuit board, the first upper clearance area, and the second upper clearance area, a first

conductor area disposed in the first upper clearance area and connected to the upper radiator to feed the upper radiator, and a second conductor area disposed in the second upper clearance area and connected to the upper radiator to feed the upper radiator are defined on an upper surface of the circuit board.

In this case, the first upper clearance area and the second upper clearance area may be areas in which the first metal layer has been removed of the upper surface of the circuit board, and the upper radiator and the upper ground may be areas in which the first metal has not been removed of the upper surface of the circuit board.

Meanwhile, a third upper clearance area that is an area in which the first metal layer has been removed of the upper surface of the circuit board and disposed between the first upper clearance area and the second upper clearance area may be further defined on the upper surface of the circuit board. In this case, a first side of the third upper clearance area may be disposed to face an end portion of the first upper clearance area adjacent to the center point of the circuit board, and a second side of the third upper clearance area adjacent to the first side of the third upper clearance area may be disposed to face an end portion of the second upper clearance area adjacent to the center point of the circuit board.

A first upper connection conductor that is an area between the first upper clearance area and the third upper clearance area and connects the upper radiator with the upper ground, and a second upper connection conductor that is an area between the second upper clearance area and the third upper clearance area and connects the upper radiator with the upper ground may be further defined on the upper surface of the circuit board.

A lower clearance area that is an area in which the second metal layer has been removed of the lower surface of the circuit board and overlaps the first upper clearance area, the second upper clearance area, the third upper clearance area, and the upper radiator, and a lower ground that is an area excluding the lower clearance area of the lower surface of the circuit board and overlaps the upper ground may be defined on the lower surface of the circuit board.

The first conductor area and the second conductor area may each include a feed conductor connected to a power source; and a feed line having a first end portion connected to the feed conductor and a second end portion connected to the upper radiator. The feed conductor may be an area in which an upper surface of the first metal layer is exposed by removing a first overlay layer among a first conductive area and a second conductive area. In this case, the circuit board may include a first matching circuit disposed in the first conductor area and a second matching circuit disposed in the second conductor area.

A first lower clearance area formed from a first side surface of the circuit board toward a center point of the circuit board to overlap the first upper clearance area, a second lower clearance area formed in a direction from a second side surface of the circuit board in contact with the first side surface of the circuit board to the center point of the circuit board to overlap the second upper clearance area and spaced apart from the first lower clearance area, a lower radiator surrounded by the first and second side surfaces of the circuit board, the first lower clearance area, and the second lower clearance area, and a lower ground surrounded by third and fourth side surfaces of the circuit board that are opposite to the first and second side surfaces of the circuit board, the first lower clearance area, and the second lower clearance area may be defined on the lower surface of the

circuit board. In this case, the lower radiator may be connected to the upper radiator through one or more via holes passing through the circuit board.

Meanwhile, a third lower clearance area that is an area in which the second metal layer has been removed of the lower surface of the circuit board, disposed between the first lower clearance area and the second lower clearance area, and overlaps the third upper clearance area defined on the upper surface of the circuit board may be further defined on the lower surface of the circuit board. In this case, a first side of the third lower clearance area may be disposed to face an end portion of the first lower clearance area adjacent to the center point of the circuit board, and a second side of the third lower clearance area adjacent to the first side may be disposed to face an end portion of the second lower clearance area adjacent to the center point of the circuit board.

A first lower connection conductor that is an area between the first lower clearance area and the third lower clearance area and connects the lower radiator with the lower ground, and a second lower connection conductor that is an area between the second lower clearance area and the third lower clearance area and connects the lower radiator with the lower ground may be further defined on the lower surface of the circuit board.

The first lower clearance area and the second lower clearance area may be areas in which the second metal layer has been removed of the lower surface of the circuit board, and the lower radiator and the lower ground may be areas in which the second metal has not been removed of the lower surface of the circuit board.

A lower clearance area that is an area in which the second metal layer has been removed of the lower surface of the circuit board and overlaps the first upper clearance area, the second upper clearance area, and the upper radiator, and a lower ground that is an area excluding the lower clearance area of the lower surface of the circuit board and overlaps the upper ground may be defined on the lower surface of the circuit board.

Advantageous Effects of Invention

According to the present disclosure, the multi-band antenna module may provide the antenna for receiving the signal in the multiple bands while preventing the degradation of isolation caused by interference between the antennas by coupling the antennas with different polarization characteristics.

In addition, the multi-band antenna module can implement the multiple input multiple output (MIMO) antenna and/or the diversity antenna by forming the two feed lines that supply power to the PIFA antenna formed of the metal layer of the circuit board and constituting the two feed lines as the radiator for resonating in the frequency band that differs from that of the PIFA antenna.

In addition, the multi-band antenna module can minimize channel loss and interference by constituting the MIMO antenna and increase the communication rate by increasing the transmission capacity together with the increase in the number of channels.

In addition, the multi-band antenna module can increase the data transmission capacity and minimize the signal loss due to channel interference by constituting the diversity antenna, thereby enabling stable communication.

In addition, the multi-band antenna module can reduce the manufacturing costs and provide a relatively thin antenna

compared to the structure in which the patch antenna is mounted by constituting the PIFA antenna using the metal layer of the circuit board.

BRIEF DESCRIPTION OF DRAWINGS

FIGS. 1 and 2 are views for describing a multi-band antenna module according to a first embodiment of the present disclosure.

FIGS. 3 and 4 are views for describing a multi-band antenna module according to a second embodiment of the present disclosure.

FIG. 5 is a view showing the multi-band antenna modules according to the first and second embodiments of the present disclosure.

FIGS. 6 and 7 are views for describing a multi-band antenna module according to a third embodiment of the present disclosure.

FIGS. 8 and 9 are views for describing a multi-band antenna module according to a fourth embodiment of the present disclosure.

FIG. 10 is a view showing the multi-band antenna modules according to the third and fourth embodiments of the present disclosure.

FIGS. 11 and 12 are views for describing a multi-band antenna module according to a fifth embodiment of the present disclosure.

FIGS. 13 and 14 are views for describing a multi-band antenna module according to a sixth embodiment of the present disclosure.

FIG. 15 is a view showing the multi-band antenna modules according to the fifth and sixth embodiments of the present disclosure.

FIGS. 16 and 17 are views for describing a multi-band antenna module according to a seventh embodiment of the present disclosure.

FIGS. 18 and 19 are views for describing a multi-band antenna module according to an eighth embodiment of the present disclosure.

FIG. 20 is a view showing the multi-band antenna modules according to the seventh and eighth embodiments of the present disclosure.

DESCRIPTION OF EMBODIMENTS

Hereinafter, exemplary embodiments according to the present disclosure will be described in detail with reference to the accompanying drawings.

The embodiments are provided to more completely describe the present disclosure to those skilled in the art, and the following embodiments may be modified in various different forms, and the scope of the present disclosure is limited to the following embodiments. Rather, the embodiments are provided to make the disclosure more faithful and complete and fully convey the spirit of the present disclosure.

Terms used herein are intended to describe specific embodiments and are not intended to limit the present disclosure. In addition, in the present specification, singular forms may include plural forms unless the context clearly indicates otherwise.

In the description of the embodiment, when each layer (film), area, pattern, or structure is described as being formed "on" or "under" a substrate, each layer (film), area, pad, or patterns, "on" and "under" include both cases of being formed "directly" or "indirectly with other elements

interposed therebetween." In addition, in principle, the reference for "above" or "under" each layer is based on the drawing.

The drawings are only intended to help understanding of the spirit of the present disclosure and should not be construed as limiting the scope of the present disclosure by the drawings. In addition, in the drawings, a relative thickness and length, or a relative size may be exaggerated for convenience and clarity of description.

A multi-band antenna module according to an embodiment of the present disclosure operates as a multi-band antenna using two antennas with different radiation types.

In other words, the multi-band antenna module operates as a multi-band antenna by coupling a directional radiation type PIFA antenna with an omni directional radiation type monopole antenna. In this case, the PIFA antenna is formed of a metal layer of a circuit board. The monopole antenna is formed of feed lines of the PIFA antenna, and the feed line is formed of the metal layer of the circuit board.

When the multi-band antenna module is composed of antennas with similar polarization, the antennas interfere with each other, thereby degrading isolation.

Therefore, the multi-band antenna module according to the embodiment of the present disclosure minimizes the interference between the antennas by providing a composite structure that combines the directional PIFA antennas with different polarizations with the non-directional monopole antenna, thereby minimizing the degradation of isolation.

Referring to FIGS. 1 and 2, the multi-band antenna module according to the first embodiment of the present disclosure includes a circuit board 100, a first upper clearance area 110a, a second upper clearance area 120a, an upper radiator 130a, an upper ground 140a, a first conductor area 150, a second conductor area 160, a first lower clearance area 110b, a second lower clearance area 120b, a lower radiator 130b, a lower ground 140b, and a via hole 170.

The circuit board 100 is a general printed circuit board and is a stacking board in which a resin layer, a metal layer, and a coverlay layer are stacked. The circuit board 100 may be further formed with another layer made of a material, such as metal or resin, interposed between the resin layer and the metal layer. The circuit board 100 may be further formed with another layer made of a material, such as metal or resin, interposed between the metal layer and a coverlay layer.

In addition, the circuit board 100 may be a stacking board in which the metal layer is stacked on each of both surfaces of the resin layer. In this case, the metal layer may be formed by printing a metal paste on a surface of the resin layer, and in addition, the metal layer may be formed on a surface of the resin layer in any of various methods.

Hereinafter, description will be made based on an example in which the circuit board 100 includes a resin layer, a first metal layer stacked on an upper surface of the resin layer, a first coverlay layer stacked on an upper surface of the first metal layer, a second metal layer stacked on a lower surface of the resin layer, and a second coverlay layer stacked on a lower surface of the second metal layer.

A first upper clearance area 110a and a second upper clearance area 120a are defined on an upper surface of the circuit board 100.

The first upper clearance area 110a is an area formed by removing the first metal layer and the first coverlay layer of the circuit board 100. For example, the first upper clearance area 110a is formed in a rectangular shape formed in a direction from a first side surface of the circuit board 100 to a center point of the circuit board 100 and is open toward the

first side surface of the circuit board 100. In this case, the first side surface is one side surface among side surfaces formed by the circuit board 100.

The second upper clearance area 120a is an area formed by removing the first metal layer and the first coverlay layer of the circuit board 100. For example, the second upper clearance area 120a is formed in a rectangular shape formed in a direction from a second side surface of the circuit board 100 to a center point of the circuit board 100 and is open toward the second side surface of the circuit board 100. In this case, the second side surface is one of the side surfaces formed by the circuit board 100 and is a side surface adjacent to the first side surface and perpendicular to the first side surface.

The upper surface of the circuit board 100 is divided into two areas through the first upper clearance area 110a and the second upper clearance area 120a. Therefore, an upper radiator 130a and an upper ground 140a are defined on the upper surface of the circuit board 100.

The upper radiator 130a is an area in which the first metal layer and the first coverlay layer of the circuit board 100 have not been removed and is an area surrounded by the first upper clearance area 110a and the second upper clearance area 120a of the upper surface of the circuit board 100.

For example, when the first upper clearance area 110a and the second upper clearance area 120a are formed in a rectangular shape, the upper radiator 130a may be defined as a rectangular area formed by a straight line extending from a first vertex at which the first and second side surfaces of the circuit board 100 are in contact with each other to the first upper clearance area 110a along the first side surface and a straight line extending from a second vertex to the second upper clearance area 120a along the second side surface.

The upper ground 140a is an area in which the first metal layer and the first coverlay layer of the circuit board 100 have not been removed and is an area surrounded by the first upper clearance area 110a and the second upper clearance area 120a of the upper surface of the circuit board 100.

For example, when the first upper clearance area 110a and the second upper clearance area 120a are formed in a rectangular shape, the upper ground 140a may be defined as a "T"-shaped area formed by a straight line extending from the third and fourth side surfaces and the first upper clearance area 110a of the circuit board 100 to a vertex in contact with the third side surface along the first side surface and a straight line extending from the second upper clearance area 120a to a vertex in contact with the fourth side surface along the second side surface.

The first conductor area 150 is defined in the first upper clearance area 110a. The first conductor area 150 is an area in which the first metal layer and/or the first coverlay layer have not been removed of the first upper clearance area 110a. The first conductor area 150 operates as a feed line for the PIFA antenna formed by the upper radiator 130a and the lower radiator 130b and at the same time, operates as a micro-strip line antenna.

The first conductor area 150 may be simultaneously formed together with the first upper clearance area 110a. In other words, the first conductor area 150 may be formed by removing the first metal layer and the first coverlay layer in an area excluding an area corresponding to the first conductor area 150 in a process of forming the first upper clearance area 110a. In this case, the first conductor area 150 may be spaced apart from an outer perimeter of the first upper

clearance area **110a** in the first upper clearance area **110a** and formed in an island pattern formed to be connected to the upper radiator **130a**.

A first feed conductor **151** and a first feed line **152** may be defined in the first conductor area **150** depending on whether the first coverlay layer is removed.

The first feed conductor **151** is an area in which the first coverlay layer has been removed of the first conductor area **150**. The first feed conductor **151** is connected to a first feed unit (see FIG. 5) and the first feed line **152**. In the first feed conductor **151**, the first coverlay layer is removed to expose the first metal layer to an upper surface thereof, and the first feed unit is connected to the upper surface to which the first metal layer is exposed.

The first feed line **152** is an area in which the first coverlay layer has not been removed of the first conductor area **150**. The first feed line **152** is connected to the first feed conductor **151** and the upper radiator **130a**. A first end portion of the first feed line **152** is connected to the first feed conductor **151**, and a second end portion of the first feed line **152** is connected to the upper radiator **130a**.

The second conductor area **160** is defined in the second upper clearance area **120a**. The second conductor area **160** is an area in which the first metal layer and/or the first coverlay layer have not been removed of the second upper clearance area **120a**. The second conductor area **160** operates as a feed line for the PIFA antenna formed by the upper radiator **130a** and the lower radiator **130b** and at the same time, operates as a micro-strip line antenna.

The second conductor area **160** may be simultaneously formed together with the second upper clearance area **120a**. In other words, the second conductor area **160** may be formed by removing the first metal layer and the first coverlay layer in an area excluding an area corresponding to the second conductor area **160** in a process of forming the second upper clearance area **120a**. In this case, the second conductor area **160** may be spaced apart from an outer perimeter of the second upper clearance area **120a** in the second upper clearance area **120a** and formed in an island pattern formed to be connected to the upper radiator **130a**.

A second feed conductor **161** and a second feed line **162** may be defined in the second conductor area **160** depending on whether the first coverlay layer is removed.

The second feed conductor **161** is an area in which the first coverlay layer has been removed of the second conductor area **160**. The second feed conductor **161** is connected to a second feed unit (see FIG. 5) and the second feed line **162**. In the second feed conductor **161**, the first coverlay layer is removed to expose the first metal layer to an upper surface thereof, and the second feed unit is connected to the upper surface to which the first metal layer is exposed.

The second feed line **162** is an area in which the first coverlay layer has not been removed of the second conductor area **160**. The second feed line **162** is connected to the second feed conductor **161** and the upper radiator **130a**. A first end portion of the second feed line **162** is connected to the second feed conductor **161**, and a second end portion of the second feed line **162** is connected to the upper radiator **130a**.

The first conductor area **150** and the second conductor area **160** are defined to be orthogonal.

The first conductor area **150** is defined to be parallel to the first side surface of the circuit board **100**, and the second conductor area **160** is defined to be parallel to the second side surface of the circuit board **100**. Therefore, a virtual straight line passing through the first conductor area **150** in

a vertical direction is perpendicular to a virtual straight line passing through the second conductor area **160** in a horizontal direction.

In other words, a first virtual straight line is defined to be parallel to the first side surface of the circuit board **100** while passing through the first feed conductor **151** and the first feed line **152** of the first conductor area **150**. The second virtual straight line is defined to be parallel to the second side surface of the circuit board **100** while passing through the second feed conductor **161** and the second feed line **162** of the second conductor area **160**. Therefore, the first virtual straight line and the second virtual straight line intersect so that an angle formed therebetween is 90 degrees, and the first conductor area **150** and the second conductor area **160** are defined to be orthogonal.

A first lower clearance area **110b** and a second lower clearance area **120b** are defined on a lower surface of the circuit board **100**.

The first lower clearance area **110b** is an area formed by removing the second metal layer and the second coverlay layer of the circuit board **100**. The first lower clearance area **110b** is defined to be disposed opposite to the first upper clearance area **110a** with the resin layer of the circuit board **100** interposed therebetween.

For example, the first lower clearance area **110b** is formed in a rectangular shape formed in a direction from the first side surface of the circuit board **100** to the center point of the circuit board **100** and is open toward the first side surface of the circuit board **100**. In this case, the first side surface is one side surface among side surfaces formed by the circuit board **100**.

The second lower clearance area **120b** is an area formed by removing the second metal layer and the second coverlay layer of the circuit board **100**. The second lower clearance area **120b** is defined to be disposed opposite to the second upper clearance area **120a** with the resin layer of the circuit board **100** interposed therebetween.

For example, the second lower clearance area **120b** is formed in a rectangular shape formed in a direction from the second side surface of the circuit board **100** to the center point of the circuit board **100** and is open toward the second side surface of the circuit board **100**. In this case, the second side surface is one of the side surfaces formed by the circuit board **100** and is a side surface adjacent to the first side surface and perpendicular to the first side surface.

The lower surface of the circuit board **100** is divided into two areas through the first lower clearance area **110b** and the second lower clearance area **120b**. Therefore, a lower radiator **130b** and a lower ground **140b** are defined on the lower surface of the circuit board **100**.

The lower radiator **130b** is an area in which the second metal layer and the second coverlay layer of the circuit board **100** have not been removed and is an area surrounded by the first lower clearance area **110b** and the second lower clearance area **120b** of the lower surface of the circuit board **100**. In this case, the lower radiator **130b** is disposed opposite to the upper radiator **130a** with the resin layer of the circuit board **100** interposed therebetween.

For example, when the first lower clearance area **110b** and the second lower clearance area **120b** are formed in a rectangular shape, the lower radiator **130b** may be defined as a rectangular area formed by a straight line extending from the first vertex at which the first and second side surfaces of the circuit board **100** are in contact with each other to the first lower clearance area **110b** along the first side surface

and a straight line extending from the second vertex to the second lower clearance area **120b** along the second side surface.

The lower ground **140b** is an area in which the second metal layer and the second coverlay layer of the circuit board **100** have not been removed and is an area surrounded by the first lower clearance area **110b** and the second lower clearance area **120b** of the lower surface of the circuit board **100**. In this case, the lower ground **140b** may be disposed opposite to the upper ground **140a** with the resin layer of the circuit board **100** interposed therebetween and connected to the upper ground **140a** through another via hole **170**.

For example, when the first lower clearance area **110b** and the second lower clearance area **120b** are formed in a rectangular shape, the lower ground **140b** may be defined as a “ $\sim$ ”-shaped area formed by a straight line extending from the third and fourth sides surfaces and the first lower clearance area **110b** of the circuit board **100** to the vertex in contact with the third side surface along the first side surface and a straight line extending from the second lower clearance area **120b** to the vertex in contact with the fourth side surface along the second side surface.

The via hole **170** connects the upper radiator **130a** with the lower radiator **130b** to form a PIFA antenna. In other words, the via hole **170** passes through the circuit board **100** (i.e., the upper radiator **130a**, the resin layer of the circuit board **100**, and the lower radiator **130b**). The via hole **170** has a metal layer (not shown) formed on an inner wall thereof or is filled with a metal to connect the first metal layer of the upper radiator **130a** with the second metal layer of the lower radiator **130b**.

As described above, the upper radiator **130a** and the lower radiator **130b** are connected through a plurality of via holes **170** and connected to the upper ground **140a** and the lower ground **140b**. The upper radiator **130a** and the lower radiator **130b** operate as PIFA antennas to which power is supplied through the first conductor area **150** and the second conductor area **160** and which resonates in a first frequency band.

In addition, the first conductor area **150** and the second conductor area **160** operate as monopole antennas that resonate in a second frequency band.

Referring to FIGS. 3 and 4, the multi-band antenna module according to the second embodiment of the present disclosure includes a circuit board **200**, a first upper clearance area **210**, a second upper clearance area **220**, a radiator **230**, an upper ground **240a**, a first conductor area **250**, a second conductor area **260**, a lower clearance area **270**, and a lower ground **240b**.

The circuit board **200** is a general printed circuit board and is a stacking board in which a resin layer, a metal layer, and a coverlay layer are stacked. The circuit board **200** may be further formed with another layer made of a material, such as metal or resin, interposed between the resin layer and the metal layer. The circuit board **200** may be further formed with another layer made of a material, such as metal or resin, interposed between the metal layer and a coverlay layer.

Hereinafter, description will be made based on an example in which the circuit board **200** includes a resin layer, a first metal layer stacked on an upper surface of the resin layer, a first coverlay layer stacked on an upper surface of the first metal layer, a second metal layer stacked on a lower surface of the resin layer, and a second coverlay layer stacked on a lower surface of the second metal layer.

A first upper clearance area **210** and a second upper clearance area **220** are defined on an upper surface of the circuit board **200**.

The first upper clearance area **210** is an area formed by removing the first metal layer and the first coverlay layer of the circuit board **200**. For example, the first upper clearance area **210** is formed in a rectangular shape formed in a direction from a first side surface of the circuit board **200** to a center point of the circuit board **200** and is open toward the first side surface of the circuit board **200**. In this case, the first side surface is one side surface among side surfaces formed by the circuit board **200**.

The second upper clearance area **220** is an area formed by removing the first metal layer and the first coverlay layer of the circuit board **200**. For example, the second upper clearance area **220** is formed in a rectangular shape formed in a direction from a first side surface of the circuit board **200** to a center point of the circuit board **200** and is open toward the second side surface of the circuit board **200**. In this case, the second side surface is one of the side surfaces formed by the circuit board **200** and is a side surface adjacent to the first side surface and perpendicular to the first side surface.

The upper surface of the circuit board **200** is divided into two areas through the first upper clearance area **210** and the second upper clearance area **220**. Therefore, the radiator **230** and the upper ground **240a** are defined on the upper surface of the circuit board **200**.

The radiator **230** is an area in which the first metal layer and the first coverlay layer of the circuit board **200** have not been removed and is an area surrounded by the first upper clearance area **210** and the second upper clearance area **220** of the upper surface of the circuit board **200**.

For example, when the first upper clearance area **210** and the second upper clearance area **220** are formed in a rectangular shape, the radiator **230** may be defined as a rectangular area formed by a straight line extending from a first vertex at which the first and second side surfaces of the circuit board **200** are in contact with each other to the first upper clearance area **210** along the first side surface and a straight line extending from a second vertex to the second upper clearance area **220** along the second side surface.

The radiator **230** is connected to the upper ground **240a** and receives power through the first conductor area **250** and the second conductor area **260**. Therefore, the radiator **230** operates as a PIFA antenna that resonates in the first frequency band, and the first conductor area **250** and the second conductor area **260** operate as monopole antennas that resonate in the second frequency band.

The upper ground **240a** is an area in which the first metal layer and the first coverlay layer of the circuit board **200** have not been removed and is an area surrounded by the first upper clearance area **210** and the second upper clearance area **220** of the upper surface of the circuit board **200**.

For example, when the first upper clearance area **210** and the second upper clearance area **220** are formed in a rectangular shape, the upper ground **240a** may be defined as a “ $\sim$ ”-shaped area formed by a straight line extending from the third and fourth sides surfaces and the first upper clearance area **210** of the circuit board **200** to a vertex in contact with the third side surface along the first side surface and a straight line extending from the second upper clearance area **220** to a vertex in contact with the fourth side surface along the second side surface.

The first conductor area **250** is defined in the first upper clearance area **210**. The first conductor area **250** is an area in which the first metal layer and/or the first coverlay layer have not been removed of the first upper clearance area **210**. The first conductor area **250** operates as a feed line for the

11

PIFA antenna formed by the radiator 230 and the lower radiator 230 and at the same time, operates as a micro-strip line antenna.

The first conductor area 250 may be simultaneously formed together with the first upper clearance area 210. In other words, the first conductor area 250 may be formed by removing the first metal layer and the first overlay layer in an area excluding an area corresponding to the first conductor area 250 in a process of forming the first upper clearance area 210. In this case, the first conductor area 250 may be spaced apart from an outer perimeter of the first upper clearance area 210 in the first upper clearance area 210 and formed in an island pattern formed to be connected to the radiator 230.

A first feed conductor 251 and a first feed line 252 may be defined in the first conductor area 250 depending on whether the first overlay layer is removed.

The first feed conductor 251 is an area in which the first overlay layer has been removed of the first conductor area 250. The first feed conductor 251 is connected to a first feed unit (see FIG. 5) and the first feed line 252. In the first feed conductor 251, the first overlay layer is removed to expose the first metal layer to an upper surface thereof, and the first feed unit is connected to the upper surface to which the first metal layer is exposed.

The first feed line 252 is an area in which the first overlay layer has not been removed of the first conductor area 250. The first feed line 252 is connected to the first feed conductor 251 and the radiator 230. A first end portion of the first feed line 252 is connected to the first feed conductor 251, and a second end portion of the first feed line 252 is connected to the radiator 230.

The second conductor area 260 is defined in the second upper clearance area 220. The second conductor area 260 is an area in which the first metal layer and/or the first overlay layer have not been removed of the second upper clearance area 220. The second conductor area 260 operates as a feed line for the PIFA antenna formed by the radiator 230 and the lower radiator 230 and at the same time, operates as a micro-strip line antenna.

The second conductor area 260 may be simultaneously formed together with the second upper clearance area 220. In other words, the second conductor area 260 may be formed by removing the first metal layer and the first overlay layer in an area excluding an area corresponding to the second conductor area 260 in a process of forming the second upper clearance area 220. In this case, the second conductor area 260 may be spaced apart from an outer perimeter of the second upper clearance area 220 in the second upper clearance area 220 and formed in an island pattern formed to be connected to the radiator 230.

A second feed conductor 261 and a second feed line 262 may be defined in the second conductor area 260 depending on whether the first overlay layer is removed.

The second feed conductor 261 is an area in which the first overlay layer has been removed of the second conductor area 260. The second feed conductor 261 is connected to a second feed unit (see FIG. 5) and the second feed line 262. In the second feed conductor 261, the first overlay layer is removed to expose the first metal layer to an upper surface thereof, and the second feed unit is connected to the upper surface to which the first metal layer is exposed.

The second feed line 262 is an area in which the first overlay layer has not been removed of the second conductor area 260. The second feed line 262 is connected to the second feed conductor 261 and the radiator 230. A first end portion of the second feed line 262 is connected to the

12

second feed conductor 261, and a second end portion of the second feed line 262 is connected to the radiator 230.

A lower clearance area 270 and a lower ground 240b are defined on the lower surface of the circuit board 200.

The lower clearance area 270 is an area formed by removing the second metal layer and the second overlay layer of the circuit board 200. The lower clearance area 270 is defined opposite to the first upper clearance area 210, the second upper clearance area 220, and the radiator 230 with the resin layer of the circuit board 200 interposed therebetween.

The lower ground 240b is an area in which the second metal layer and the second overlay layer have not been removed of the circuit board 200 and is an area excluding the lower clearance area 270 of the lower surface of the circuit board 200. In this case, the lower ground 240b is disposed opposite to the upper ground 240a with the resin layer of the circuit board 200 interposed therebetween. Here, the lower ground 240b may be connected to the upper ground 240a through a via hole.

Referring to FIG. 5, in the multi-band antenna modules according to the first and second embodiments of the present disclosure, the radiators 130 and 230 defined on the circuit boards 100 and 200 are connected to the first feed lines through the first conductor areas 150 and 250, connected to the second feed lines through the second conductor areas 160 and 260, and connected to the grounds 140 and 240 defined on the circuit boards 100 and 200. Therefore, the radiators 130 and 230 defined on the circuit boards 100 and 200 operate as the PIFA antennas that resonate in the first frequency band, and the first conductor areas 150 and 250 and the second conductor areas 160 and 260 operate as monopole antennas that resonate in the second frequency band.

Referring to FIGS. 6 and 7, the multi-band antenna module according to the third embodiment of the present disclosure is a modified structure of the multi-band antenna module according to the first embodiment of the present disclosure.

In this case, since the circuit board 100, the first upper clearance area 110a, the second upper clearance area 120a, the upper radiator 130a, the upper ground 140a, the first conductor area 150, the second conductor area 160, the first lower clearance area 110b, the second lower clearance area 120b, the lower radiator 130b, the lower ground 140b, and the via hole 170 are the same as the circuit board 300, the first upper clearance area 310a, the second upper clearance area 320a, the upper radiator 330a, the upper ground 340a, the first conductor area 350, the second conductor area 360, the first lower clearance area 310b, the second lower clearance area 320b, the lower radiator 330b, the lower ground 340b, and the via hole 370 of the multi-band antenna module according to the first embodiment, detailed descriptions thereof are omitted.

A first matching circuit 380 for impedance adjustment may be connected to the first conductor area 350. The first matching circuit 380 is disposed above the first conductor area 350 to generate an impedance close to 50 ohms, thereby minimizing return loss (Γ).

A second matching circuit 390 for impedance adjustment may be connected to the second conductor area 360. The second matching circuit 390 is disposed above the second conductor area 360 to generate an impedance close to 50 ohms, thereby minimizing return loss (Γ).

Referring to FIGS. 8 and 9, the multi-band antenna module according to the fourth embodiment of the present

disclosure is a modified structure of the multi-band antenna module according to the second embodiment of the present disclosure.

In this case, since a circuit board 400, a first upper clearance area 410, a second upper clearance area 420, a radiator 430, an upper ground 440a, a first conductor area 450, a second conductor area 460, a lower clearance area 490, and a lower ground 440b are the same as the circuit board 200, the first upper clearance area 210, the second upper clearance area 220, the radiator 230, the upper ground 240a, the first conductor area 250, the second conductor area 260, the lower clearance area 270, and the lower ground 240b of the multi-band antenna module according to the second embodiment, detailed descriptions thereof are omitted.

A first matching circuit 482 for impedance adjustment may be connected to the first conductor area 450. The first matching circuit 482 is disposed above the first conductor area 450 to generate an impedance close to 50 ohms, thereby minimizing return loss (Γ).

A second matching circuit 484 for impedance adjustment may be connected to the second conductor area 460. The second matching circuit 484 is disposed above the second conductor area 460 to generate an impedance close to 50 ohms, thereby minimizing return loss (Γ).

Referring to FIG. 10, in the multi-band antenna modules according to the third and fourth embodiments of the present disclosure, the radiators 330 and 430 defined on the circuit boards 300 and 400 are connected to the first feed lines through the first conductor areas 350 and 450, connected to the second feed lines through the second conductor areas 360 and 460, and connected to the grounds 340 and 440 defined on the circuit boards 300 and 400.

Therefore, the radiators 330 and 430 defined on the circuit boards 300 and 400 operate as the PIFA antennas that resonate in the first frequency band, and the first conductor areas 350 and 450 and the second conductor areas 360 and 460 operate as monopole antennas that resonate in the second frequency band. In this case, the first matching circuits 380 and 482 and the second matching circuits 390 and 484 are disposed in the first conductor areas 350 and 450 and the second conductor areas 360 and 460 to minimize the return losses (Γ) of the PIFA antenna and the monopole antenna.

Referring to FIGS. 11 and 12, the multi-band antenna module according to the fifth embodiment of the present disclosure includes a circuit board 500, a first upper clearance area 510a, a second upper clearance area 520a, a third upper clearance area 530a, an upper radiator 540a, an upper ground 550a, a first upper connection conductor 552a, a second upper connection conductor 554a, a first conductor area 560, a second conductor area 570, a first lower clearance area 510b, a second lower clearance area 520b, a third lower clearance area 530b, a lower radiator 540b, a lower ground 550b, a first lower connection conductor 552b, a second lower connection conductor 554b, and a via hole 580.

The circuit board 500 is a general printed circuit board and is a stacking board in which a resin layer, a metal layer, and a coverlay layer are stacked. The circuit board 500 may be further formed with another layer made of a material, such as metal or resin, interposed between the resin layer and the metal layer. The circuit board 500 may be further formed with another layer made of a material, such as metal or resin, interposed between the metal layer and a coverlay layer.

Hereinafter, description will be made based on an example in which the circuit board 500 includes a resin layer, a first metal layer stacked on an upper surface of the resin layer, a first coverlay layer stacked on an upper surface of the first metal layer, a second metal layer stacked on a lower surface of the resin layer, and a second coverlay layer stacked on a lower surface of the second metal layer.

The first upper clearance area 510a, the second upper clearance area 520a, and the third upper clearance area 530a are defined on an upper surface of the circuit board 500.

The first upper clearance area 510a is an area formed by removing the first metal layer and the first coverlay layer of the circuit board 500. For example, the first upper clearance area 510a is formed in a rectangular shape formed in a direction from a first side surface of the circuit board 500 to a center point of the circuit board 500 and is open toward the first side surface of the circuit board 500. In this case, the first side surface is one side surface among side surfaces formed by the circuit board 500.

The second upper clearance area 520a is an area formed by removing the first metal layer and the first coverlay layer of the circuit board 500. For example, the second upper clearance area 520a is formed in a rectangular shape formed in a direction from a second side surface of the circuit board 500 to a center point of the circuit board 500 and is open toward the second side surface of the circuit board 500. In this case, the second side surface is one of the side surfaces formed by the circuit board 500 and is a side surface adjacent to the first side surface and perpendicular to the first side surface.

The third upper clearance area 530a is an area formed by removing the first metal layer and the first coverlay layer of the circuit board 500. The third upper clearance area 530a is defined between the first upper clearance area 510a and the second upper clearance area. For example, the third upper clearance area 530a is defined in a rectangular shape. The third upper clearance area 530a is defined to have adjacent two sides respectively facing one sides of the first upper clearance area 510a and the second upper clearance area 520a. In this case, the third upper clearance area 530a is defined to be spaced by a predetermined distance from the first upper clearance area 510a and the second upper clearance area 520a.

The upper surface of the circuit board 500 is partitioned into four areas through the first upper clearance area 510a, the second upper clearance area 520a, and the third upper clearance area 530a. Therefore, the upper radiator 540a, the upper ground 550a, the first upper connection conductor 552a, and the second upper connection conductor 554a are defined on the upper surface of the circuit board 500.

The upper radiator 540a is an area in which the first metal layer and the first coverlay layer of the circuit board 500 have not been removed and is an area surrounded by the first upper clearance area 510a, the second upper clearance area 520a, and the third upper clearance area 530a of the upper surface of the circuit board 500.

For example, when the first upper clearance area 510a and the second upper clearance area 520a are formed in a rectangular shape, the upper radiator 540a may be defined as a rectangular area formed by a straight line extending from a first vertex at which the first and second side surfaces of the circuit board 500 are in contact with each other to the first upper clearance area 510a along the first side surface and a straight line extending from a second vertex to the second upper clearance area 520a along the second side surface. In this case, a vertex with which two sides of the upper radiator 540a respectively facing the first and second

side surfaces of the circuit board 500 are in contact corresponds to a vertex with which two sides of the third upper clearance area 530a facing the first upper clearance area 510a and the second upper clearance area 520a are in contact.

The upper ground 550a is an area in which the first metal layer and the first coverlay layer of the circuit board 500 have not been removed and is an area surrounded by the first upper clearance area 510a, the second upper clearance area 520a, and the third upper clearance area 530a of the upper surface of the circuit board 500. For example, the upper ground 550a is a “-”-shaped area that surrounds the two sides of a quadrangle formed by the first upper clearance area 510a, the second upper clearance area 520a, and the upper radiator 540a of the upper surface of the circuit board 500.

The first upper connection conductor 552a is an area in which the first metal layer and the first coverlay layer of the circuit board 500 have not been removed. The first upper connection conductor 552a is defined between the first upper clearance area 510a and the third upper clearance area 530a of the upper surface of the circuit board 500 to connect the upper radiator 540a with the upper ground 550a.

The second upper connection conductor 554a is an area in which the first metal layer and the first coverlay layer of the circuit board 500 have not been removed. The second upper connection conductor 554a is defined between the second upper clearance area 520a and the third upper clearance area 530a of the upper surface of the circuit board 500 to connect the upper radiator 540a with the upper ground 550a.

The first conductor area 560 is defined in the first upper clearance area 510a. The first conductor area 560 is an area in which the first metal layer and/or the first coverlay layer have not been removed of the first upper clearance area 510a. The first conductor area 560 operates as a feed line for the PIFA antenna formed by the upper radiator 540a and the lower radiator 540b and at the same time, operates as a micro-strip line antenna.

The first conductor area 560 may be simultaneously formed together with the first upper clearance area 510a. In other words, the first conductor area 560 may be formed by removing the first metal layer and the first coverlay layer in an area excluding an area corresponding to the first conductor area 560 in a process of forming the first upper clearance area 510a. In this case, the first conductor area 560 may be spaced apart from an outer perimeter of the first upper clearance area 510a in the first upper clearance area 510a and formed in an island pattern formed to be connected to the upper radiator 540a.

A first feed conductor 561 and a first feed line 562 may be defined in the first conductor area 560 depending on whether the first coverlay layer is removed.

The first feed conductor 561 is an area in which the first coverlay layer has been removed of the first conductor area 560. The first feed conductor 561 is connected to a first feed unit (see FIG. 5) and the first feed line 562. In the first feed conductor 561, the first coverlay layer is removed to expose the first metal layer to an upper surface thereof, and the first feed unit is connected to the upper surface to which the first metal layer is exposed.

The first feed line 562 is an area in which the first coverlay layer has not been removed of the first conductor area 560. The first feed line 562 is connected to the first feed conductor 561 and the upper radiator 540a. A first end portion of the first feed line 562 is connected to the first feed conductor 561, and a second end portion of the first feed line 562 is connected to the upper radiator 540a.

The second conductor area 570 is defined in the second upper clearance area 520a. The second conductor area 570 is an area in which the first metal layer and/or the first coverlay layer have not been removed of the second upper clearance area 520a. The second conductor area 570 operates as a feed line for the PIFA antenna formed by the upper radiator 540a and the lower radiator 540b and at the same time, operates as a micro-strip line antenna.

The second conductor area 570 may be simultaneously formed together with the second upper clearance area 520a. In other words, the second conductor area 570 may be formed by removing the first metal layer and the first coverlay layer in an area excluding an area corresponding to the second conductor area 570 in a process of forming the second upper clearance area 520a. In this case, the second conductor area 570 may be spaced apart from an outer perimeter of the second upper clearance area 520a in the second upper clearance area 520a and formed in an island pattern formed to be connected to the upper radiator 540a.

A second feed conductor 571 and a second feed line 572 may be defined in the second conductor area 570 depending on whether the first coverlay layer is removed.

The second feed conductor 571 is an area in which the first coverlay layer has been removed of the second conductor area 570. The second feed conductor 571 is connected to a second feed unit (see FIG. 5) and the second feed line 572. In the second feed conductor 571, the first coverlay layer is removed to expose the first metal layer to an upper surface thereof, and the second feed unit is connected to the upper surface to which the first metal layer is exposed.

The second feed line 572 is an area in which the first coverlay layer has not been removed of the second conductor area 570. The second feed line 572 is connected to the second feed conductor 571 and the upper radiator 540a. A first end portion of the second feed line 572 is connected to the second feed conductor 571, and a second end portion of the second feed line 572 is connected to the upper radiator 540a.

The first lower clearance area 510b, the second lower clearance area 520b, and the third lower clearance area 530b are defined on a lower surface of the circuit board 500.

The first lower clearance area 510b is an area formed by removing the second metal layer and the second coverlay layer of the circuit board 500. The first lower clearance area 510b is defined to be disposed opposite to the first upper clearance area 510a with the resin layer of the circuit board 500 interposed therebetween.

For example, the first lower clearance area 510b is formed in a rectangular shape formed in a direction from the first side surface of the circuit board 500 to the center point of the circuit board 500 and is open toward the first side surface of the circuit board 500. In this case, the first side surface is one side surface among side surfaces formed by the circuit board 500.

The second lower clearance area 520b is an area formed by removing the second metal layer and the second coverlay layer of the circuit board 500. The second lower clearance area 520b is defined to be disposed opposite to the second upper clearance area 520a with the resin layer of the circuit board 500 interposed therebetween.

For example, the second lower clearance area 520b is formed in a rectangular shape formed in a direction from the second side surface of the circuit board 500 to the center point of the circuit board 500 and is open toward the second side surface of the circuit board 500. In this case, the second side surface is one of the side surfaces formed by the circuit

board 500 and is a side surface adjacent to the first side surface and perpendicular to the first side surface.

The third lower clearance area 530b is an area formed by removing the second metal layer and the second coverlay layer of the circuit board 500. The third lower clearance area 530b is defined between the first lower clearance area 510b and the second lower clearance area. The third lower clearance area 530b is defined to be disposed opposite to the third upper clearance area 530a with the resin layer of the circuit board 500 interposed therebetween.

For example, the third lower clearance area 530b is defined in a quadrangular shape. The third lower clearance area 530b is defined to have adjacent two sides respectively facing one sides of the first lower clearance area 510b and the second lower clearance area 520b. In this case, the third lower clearance area 530b is defined to be spaced by a predetermined distance from the first lower clearance area 510b and the second lower clearance area 520b.

The lower surface of the circuit board 500 is partitioned into four areas through the first lower clearance area 510b, the second lower clearance area 520b, and the third lower clearance area 530b. Therefore, the lower radiator 540b, the lower ground 550b, the first lower connection conductor 552b, and the second lower connection conductor 554b are defined on the lower surface of the circuit board 500.

The lower radiator 540b is an area in which the second metal layer and the second coverlay layer of the circuit board 500 have not been removed and is an area surrounded by the first lower clearance area 510b, the second lower clearance area 520b, and the third lower clearance area 530b of the lower surface of the circuit board 500. In this case, the lower radiator 540b is disposed opposite to the upper radiator 540a with the resin layer of the circuit board 500 interposed therebetween.

The lower ground 550b is an area in which the second metal layer and the second coverlay layer of the circuit board 500 have not been removed and is an area surrounded by the first lower clearance area 510b, the second lower clearance area 520b, and the third lower clearance area 530b of the lower surface of the circuit board 500. In this case, the lower ground 550b may be disposed opposite to the upper ground 550a with the resin layer of the circuit board 500 interposed therebetween and connected to the upper ground 550a through another via hole 580.

The first lower connection conductor 552b is an area in which the first metal layer and the first coverlay layer of the circuit board 500 have not been removed. The first lower connection conductor 552b is defined between the first lower clearance area 510b and the third lower clearance area 530b of the lower surface of the circuit board 500 to connect the lower radiator 540b with the lower ground 550b.

The second lower connection conductor 554b is an area in which the second metal layer and the second coverlay layer of the circuit board 500 have not been removed. The second lower connection conductor 554b is defined between the second lower clearance area 520b and the third lower clearance area 530b of the lower surface of the circuit board 500 to connect the lower radiator 540b with the lower ground 550b.

The via hole 580 connects the upper radiator 540a with the lower radiator 540b to form a PIFA antenna. In other words, the via hole 580 passes through the circuit board 500 (i.e., the upper radiator 540a, the resin layer of the circuit board 500, and the lower radiator 540b). The via hole 580 has a metal layer (not shown) formed on an inner wall

thereof or is filled with a metal to connect the first metal layer of the upper radiator 540a with the second metal layer of the lower radiator 540b.

As described above, the upper radiator 540a and the lower radiator 540b are connected through a plurality of via holes 580 and connected to the upper ground 550a and the lower ground 550b. The upper radiator 540a and the lower radiator 540b operate as PIFA antennas to which power is supplied through the first conductor area 560 and the second conductor area 570 and which resonates in a first frequency band.

In addition, the first conductor area 560 and the second conductor area 570 operate as monopole antennas that resonate in the second frequency band.

Referring to FIGS. 13 and 14, the multi-band antenna module according to the sixth embodiment of the present disclosure includes a circuit board 600, a first upper clearance area 610, a second upper clearance area 620, a third upper clearance area 630, a radiator 640, an upper ground 650a, a first upper connection conductor 652, a second upper connection conductor 654, a first conductor area 660, a second conductor area 670, a lower clearance area 680, and a lower ground 650b.

The circuit board 600 is a general printed circuit board and is a stacking board in which a resin layer, a metal layer, and a coverlay layer are stacked. The circuit board 600 may be further formed with another layer made of a material, such as metal or resin, interposed between the resin layer and the metal layer. The circuit board 600 may be further formed with another layer made of a material, such as metal or resin, interposed between the metal layer and a coverlay layer.

Hereinafter, description will be made based on an example in which the circuit board 600 includes a resin layer, a first metal layer stacked on an upper surface of the resin layer, a first coverlay layer stacked on an upper surface of the first metal layer, a second metal layer stacked on a lower surface of the resin layer, and a second coverlay layer stacked on a lower surface of the second metal layer.

The first upper clearance area 610, the second upper clearance area 620, and the third upper clearance area 630 are defined on an upper surface of the circuit board 600.

The first upper clearance area 610 is an area formed by removing the first metal layer and the first coverlay layer of the circuit board 600. For example, the first upper clearance area 610 is formed in a rectangular shape formed in a direction from a first side surface of the circuit board 600 to a center point of the circuit board 600 and is open toward the first side surface of the circuit board 600. In this case, the first side surface is one side surface among side surfaces formed by the circuit board 600.

The second upper clearance area 620 is an area formed by removing the first metal layer and the first coverlay layer of the circuit board 600. For example, the second upper clearance area 620 is formed in a rectangular shape formed in a direction from a first side surface of the circuit board 600 to a center point of the circuit board 600 and is open toward the second side surface of the circuit board 600. In this case, the second side surface is one of the side surfaces formed by the circuit board 600 and is a side surface adjacent to the first side surface and perpendicular to the first side surface.

The third upper clearance area 630 is an area formed by removing the first metal layer and the first coverlay layer of the circuit board 600. The third upper clearance area 630 is defined between the first upper clearance area 610 and the second upper clearance area. For example, the third upper clearance area 630 is defined in a quadrangular shape. The third upper clearance area 630 is defined to have adjacent

two sides respectively facing one sides of the first upper clearance area **610** and the second upper clearance area **620**. In this case, the third upper clearance area **630** is defined to be spaced by a predetermined distance from the first upper clearance area **610** and the second upper clearance area **620**.

The upper surface of the circuit board **600** is partitioned into four areas through the first upper clearance area **610**, the second upper clearance area **620**, and the third upper clearance area **630**. Therefore, the radiator **640**, the upper ground **650a**, the first upper connection conductor **652**, and the second upper connection conductor **654** are defined on the upper surface of the circuit board **600**.

The radiator **640** is an area in which the first metal layer and the first coverlay layer of the circuit board **600** have not been removed and is an area surrounded by the first upper clearance area **610**, the second upper clearance area **620**, and the third upper clearance area **630** of the upper surface of the circuit board **600**.

For example, when the first upper clearance area **610** and the second upper clearance area **620** are formed in a rectangular shape, the radiator **640** may be defined as a rectangular area formed by a straight line extending from a first vertex at which the first and second side surfaces of the circuit board **600** are in contact with each other to the first upper clearance area **610** along the first side surface and a straight line extending from a second vertex to the second upper clearance area **620** along the second side surface. In this case, a vertex with which two sides of the radiator **640** respectively facing the first and second side surfaces of the circuit board **600** are in contact corresponds to a vertex with which two sides of the third upper clearance area **630** facing the first upper clearance area **610** and the second upper clearance area **620** are in contact.

The upper ground **650a** is an area in which the first metal layer and the first coverlay layer of the circuit board **600** have not been removed and is an area surrounded by the first upper clearance area **610**, the second upper clearance area **620**, and the third upper clearance area **630** of the upper surface of the circuit board **600**. For example, the upper ground **650a** is a “-”-shaped area that surrounds the two sides of a quadrangle formed by the first upper clearance area **610**, the second upper clearance area **620**, and the radiator **640** of the upper surface of the circuit board **600**.

The first upper connection conductor **652** is an area in which the first metal layer and the first coverlay layer of the circuit board **600** have not been removed. The first upper connection conductor **652** is defined between the first upper clearance area **610** and the third upper clearance area **630** of the upper surface of the circuit board **600** to connect the radiator **640** with the upper ground **650a**.

The second upper connection conductor **654** is an area in which the first metal layer and the first coverlay layer of the circuit board **600** have not been removed. The second upper connection conductor **654** is defined between the second upper clearance area **620** and the third upper clearance area **630** of the upper surface of the circuit board **600** to connect the radiator **640** with the upper ground **650a**.

The first conductor area **660** is defined in the first upper clearance area **610**. The first conductor area **660** is an area in which the first metal layer and/or the first coverlay layer have not been removed of the first upper clearance area **610**. The first conductor area **660** operates as a feed line for the PIFA antenna formed by the radiator **640** and the lower radiator **640** and at the same time, operates as a micro-strip line antenna.

The first conductor area **660** may be simultaneously formed together with the first upper clearance area **610**. In

other words, the first conductor area **660** may be formed by removing the first metal layer and the first coverlay layer in an area excluding an area corresponding to the first conductor area **660** in a process of forming the first upper clearance area **610**. In this case, the first conductor area **660** may be spaced apart from an outer perimeter of the first upper clearance area **610** and formed in an island pattern formed to be connected to the radiator **640**.

10 A first feed conductor **661** and a first feed line **662** may be defined in the first conductor area **660** depending on whether the first coverlay layer is removed.

The first feed conductor **661** is an area in which the first coverlay layer has been removed of the first conductor area **660**. The first feed conductor **661** is connected to a first feed unit (see FIG. 5) and the first feed line **662**. In the first feed conductor **661**, the first coverlay layer is removed to expose the first metal layer to an upper surface thereof, and the first feed unit is connected to the upper surface to which the first metal layer is exposed.

15 The first feed line **662** is an area in which the first coverlay layer has not been removed of the first conductor area **660**. The first feed line **662** is connected to the first feed conductor **661** and the radiator **640**. A first end portion of the first feed line **662** is connected to the first feed conductor **661**, and a second end portion of the first feed line **662** is connected to the radiator **640**.

20 The second conductor area **670** is defined in the second upper clearance area **620**. The second conductor area **670** is an area in which the first metal layer and/or the first coverlay layer have not been removed of the second upper clearance area **620**. The second conductor area **670** operates as a feed line for the PIFA antenna formed by the radiator **640** and the lower radiator **640** and at the same time, operates as a micro-strip line antenna.

25 The second conductor area **670** may be simultaneously formed together with the second upper clearance area **620**. In other words, the second conductor area **670** may be formed by removing the first metal layer and the first coverlay layer in an area excluding an area corresponding to the second conductor area **670** in a process of forming the second upper clearance area **620**. In this case, the second conductor area **670** may be spaced apart from an outer perimeter of the second upper clearance area **620** and formed in an island pattern formed to be connected to the radiator **640**.

30 A second feed conductor **671** and a second feed line **672** may be defined in the second conductor area **670** depending on whether the first coverlay layer is removed.

35 The second feed conductor **671** is an area in which the first coverlay layer has been removed of the second conductor area **670**. The second feed conductor **671** is connected to a second feed unit (see FIG. 5) and the second feed line **672**. In the second feed conductor **671**, the first coverlay layer is removed to expose the first metal layer to an upper surface thereof, and the second feed unit is connected to the upper surface to which the first metal layer is exposed.

40 The second feed line **672** is an area in which the first coverlay layer has not been removed of the second conductor area **670**. The second feed line **672** is connected to the second feed conductor **671** and the radiator **640**. A first end portion of the second feed line **672** is connected to the second feed conductor **671**, and a second end portion of the second feed line **672** is connected to the radiator **640**.

45 A lower clearance area **680** and a lower ground **650b** are defined on the lower surface of the circuit board **600**.

The lower clearance area **680** is an area formed by removing the second metal layer and the second coverlay layer of the circuit board **600**. The lower clearance area **680** is defined to be disposed opposite to the area including the first upper clearance area **610**, the second upper clearance area **620**, the third upper clearance area **630**, the radiator **640**, the first upper connection conductor **652**, and the second upper connection conductor **654** with the resin layer of the circuit board **600** interposed therebetween.

The lower ground **650b** is an area in which the second metal layer and the second coverlay layer have not been removed of the circuit board **600** and is an area excluding the lower clearance area **680** of the lower surface of the circuit board **600**. In this case, the lower ground **650b** is disposed opposite to the upper ground **650a** with the resin layer of the circuit board **600** interposed therebetween. Here, the lower ground **650b** may be connected to the upper ground **650a** through a via hole.

Referring to FIG. 15, in the multi-band antenna modules according to the third and fourth embodiments of the present disclosure, the radiators **540** and **640** defined on the circuit boards **500** and **600** are connected to the first feed lines through the first conductor areas **560** and **660** and connected to the second feed lines through the second conductor areas **570** and **670**. The radiators **540** and **640** are connected to the grounds **550** and **650** defined on the circuit boards **500** and **600** through two ground lines **552** and **650** and **554** and **654**. Therefore, the radiators **540** and **640** defined on the circuit boards **500** and **600** operate as the PIFA antennas that resonate in the first frequency band, and the first conductor areas **560** and **660** and the second conductor areas **570** and **670** operate as monopole antennas that resonate in the second frequency band.

Referring to FIGS. 16 and 17, the multi-band antenna module according to the seventh embodiment of the present disclosure is a modified structure of the multi-band antenna module according to the fifth embodiment of the present disclosure.

In this case, a circuit board **700**, a first upper clearance area **710a**, a second upper clearance area **720a**, a third upper clearance area **730a**, an upper radiator **740a**, an upper ground **750a**, a first upper connection conductor **752a**, a second upper connection conductor **754a**, a first conductor area **760**, a second conductor area **770**, a first lower clearance area **710b**, a second lower clearance area **720b**, a third lower clearance area **730b**, a lower radiator **740b**, a lower ground **750b**, a first lower connection conductor **752b**, a second lower connection conductor **754b**, and a via hole **780** are the same as the circuit board **500**, the first upper clearance area **510a**, the second upper clearance area **520a**, the third upper clearance area **530a**, the upper radiator **540a**, the upper ground **550a**, the first upper connection conductor **552a**, the second upper connection conductor **554a**, the first conductor area **560**, the second conductor area **570**, the first lower clearance area **510b**, the second lower clearance area **520b**, the third lower clearance area **530b**, the lower radiator **540b**, the lower ground **550b**, the first lower connection conductor **552b**, the second lower connection conductor **554b**, and the via hole **580** of the multi-band antenna module according to the fifth embodiment, detailed descriptions thereof are omitted.

A first matching circuit **792** for impedance adjustment may be connected to the first conductor area **760**. The first matching circuit **792** is disposed above the first conductor area **760** to generate an impedance close to 50 ohms, thereby minimizing return loss (Γ).

A second matching circuit **794** for impedance adjustment may be connected to the second conductor area **770**. The second matching circuit **794** is disposed above the second conductor area **770** to generate an impedance close to 50 ohms, thereby minimizing return loss (Γ).

Referring to FIGS. 18 and 19, the multi-band antenna module according to the eighth embodiment of the present disclosure is a modified structure of the multi-band antenna module according to the sixth embodiment of the present disclosure.

In this case, since a circuit board **800**, a first upper clearance area **810**, a second upper clearance area **820**, a third upper clearance area **830**, a radiator **840**, an upper ground **850a**, a first upper connection conductor **852**, a second upper connection conductor **854**, a first conductor area **860**, a second conductor area **870**, a lower clearance area **890**, and a lower ground **850b** are the same as the circuit board **600**, the first upper clearance area **610**, the second upper clearance area **620**, the third upper clearance area **630**, the radiator **640**, the upper ground **650a**, the first upper connection conductor **652**, the second upper connection conductor **654**, the first conductor area **660**, the second conductor area **670**, the lower clearance area **680**, and the lower ground **650b** of the multi-band antenna module according to the sixth embodiment, detailed descriptions thereof are omitted.

A first matching circuit **882** for impedance adjustment may be connected to the first conductor area **810**. The first matching circuit **882** is disposed above the first conductor area **810** to generate an impedance close to 50 ohms, thereby minimizing return loss (Γ).

A second matching circuit **884** for impedance adjustment may be connected to the second conductor area **820**. The second matching circuit **884** is disposed above the second conductor area **820** to generate an impedance close to 50 ohms, thereby minimizing return loss (Γ).

Referring to FIG. 20, in the multi-band antenna modules according to the seventh and eighth embodiments of the present disclosure, the radiators **740** and **840** defined on the circuit boards **700** and **800** are connected to the first feed lines through the first conductor areas **760** and **860**, connected to the second feed lines through the second conductor areas **770** and **870**, and connected to the grounds **750** and **850** defined on the circuit boards **700** and **800** through two ground lines **752** and **754** and **852** and **854**. Therefore, the radiators **740** and **840** defined on the circuit boards **700** and **800** operate as the PIFA antennas that resonate in the first frequency band, and the first conductor areas **760** and **860** and the second conductor areas **770** and **870** operate as monopole antennas that resonate in the second frequency band. In this case, the first matching circuits **780** and **882** and the second matching circuits **790** and **884** are respectively disposed in the first conductor areas **760** and **860** and the second conductor areas **770** and **870** to minimize the return losses (Γ) of the PIFA antenna and the monopole antenna.

The above description is merely the exemplary description of the technical spirit of the present disclosure, and those skilled in the art to which the present disclosure pertains will be able to variously modify and change the present disclosure without departing from the essential characteristics of the present disclosure. Therefore, the embodiments disclosed in the present disclosure are not intended to limit the technical spirit of the present disclosure, but intended to describe the same, and the scope of the technical spirit of the present disclosure is not limited by these embodiments. The scope of the present disclosure should be construed according to the appended claims, and all tech-

nical spirits within the equivalent range should be construed as being included in the scope of the present disclosure.

The invention claimed is:

1. A multi-band antenna module comprising:
a circuit board configured by stacking a first metal layer on an upper surface of a resin layer and stacking a second metal layer on a lower surface of the resin layer, wherein a first upper clearance area formed in a direction from a first side surface of the circuit board toward a center point of the circuit board,
a second upper clearance area formed in a direction from a second side surface of the circuit board in contact with the first side surface of the circuit board to the center point of the circuit board and spaced apart from the first upper clearance area,
an upper radiator surrounded by the first and second side surfaces of the circuit board, the first upper clearance area, and the second upper clearance area,
an upper ground surrounded by third and fourth side surfaces of the circuit board that are opposite to the first and second side surfaces of the circuit board, the first upper clearance area, and the second upper clearance area,
a first conductor area disposed in the first upper clearance area and connected to the upper radiator to feed the upper radiator, and
a second conductor area disposed in the second upper clearance area and connected to the upper radiator to feed the upper radiator are defined on an upper surface of the circuit board.

2. The multi-band antenna module of claim 1, wherein the first upper clearance area and the second upper clearance area are areas in which the first metal layer has been removed of the upper surface of the circuit board, and the upper radiator and the upper ground are areas in which the first metal layer has not been removed of the upper surface of the circuit board.

3. The multi-band antenna module of claim 1, wherein a third upper clearance area that is an area in which the first metal layer has been removed of the upper surface of the circuit board and disposed between the first upper clearance area and the second upper clearance area is further defined on the upper surface of the circuit board.

4. The multi-band antenna module of claim 3, wherein a first side of the third upper clearance area is disposed to face an end portion of the first upper clearance area adjacent to the center point of the circuit board, and

- a second side of the third upper clearance area adjacent to the first side of the third upper clearance area is disposed to face an end portion of the second upper clearance area adjacent to the center point of the circuit board.

5. The multi-band antenna module of claim 3, wherein a first upper connection conductor that is an area between the first upper clearance area and the third upper clearance area and connects the upper radiator with the upper ground, and

- a second upper connection conductor that is an area between the second upper clearance area and the third upper clearance area and connects the upper radiator with the upper ground are further defined on the upper surface of the circuit board.

6. The multi-band antenna module of claim 3, wherein a lower clearance area that is an area in which the second metal layer has been removed of the lower surface of the circuit board and overlaps the first upper clearance area, the second upper clearance area, the third upper clearance area, and the upper radiator, and

a lower ground that is an area excluding the lower clearance area of the lower surface of the circuit board and overlaps the upper ground are defined on the lower surface of the circuit board.

7. The multi-band antenna module of claim 1, wherein the first conductor area and the second conductor area each include:

- 10 a feed conductor connected to a power source; and a feed line having a first end portion connected to the feed conductor and a second end portion connected to the upper radiator.

8. The multi-band antenna module of claim 7, wherein a first virtual straight line parallel to the first side surface of the circuit board while passing through the feed conductor and the feed line of the first conductor area is orthogonal to a second virtual straight line parallel to the second side surface of the circuit board while passing through the feed conductor and the feed line of the second conductor area.

9. The multi-band antenna module of claim 1, wherein the circuit board includes:

- 15 a first matching circuit disposed in the first conductor area; and a second matching circuit disposed in the second conductor area.

10. The multi-band antenna module of claim 1, wherein a first lower clearance area formed in a direction from a first side surface of the circuit board toward a center point of the circuit board to overlap the first upper clearance area,

- 20 a second lower clearance area formed in a direction from a second side surface of the circuit board in contact with the first side surface of the circuit board to the center point of the circuit board to overlap the second upper clearance area and spaced apart from the first lower clearance area,

a lower radiator surrounded by the first and second side surfaces of the circuit board, the first lower clearance area, and the second lower clearance area, and

- 25 a lower ground surrounded by third and fourth side surfaces of the circuit board that are opposite to the first and second side surfaces of the circuit board, the first lower clearance area, and the second lower clearance area are defined on the lower surface of the circuit board.

11. The multi-band antenna module of claim 10, wherein the lower radiator is connected to the upper radiator through one or more via holes passing through the circuit board.

12. The multi-band antenna module of claim 10, wherein a third lower clearance area that is an area in which the second metal layer has been removed of the lower surface of the circuit board, disposed between the first lower clearance area and the second lower clearance area, and overlaps the third upper clearance area defined on the upper surface of the circuit board is further defined on the lower surface of the circuit board.

13. The multi-band antenna module of claim 12, wherein a first side of the third lower clearance area is disposed to face an end portion of the first lower clearance area adjacent to the center point of the circuit board, and

- 30 a second side of the third lower clearance area adjacent to the first side is disposed to face an end portion of the second lower clearance area adjacent to the center point of the circuit board.

14. The multi-band antenna module of claim 12, wherein a first lower connection conductor that is an area between the first lower clearance area and the third lower clearance area and connects the lower radiator with the lower ground, and

a second lower connection conductor that is an area between the second lower clearance area and the third lower clearance area and connects the lower radiator with the lower ground are further defined on the lower surface of the circuit board. 5

15. The multi-band antenna module of claim 10, wherein the first lower clearance area and the second lower clearance area are areas in which the second metal layer has been removed of the lower surface of the circuit board, and the lower radiator and the lower ground are areas in which 10 the second metal has not been removed of the lower surface of the circuit board.

16. The multi-band antenna module of claim 1, wherein a lower clearance area that is an area in which the second metal layer has been removed of the lower surface of the 15 circuit board and overlaps the first upper clearance area, the second upper clearance area, and the upper radiator, and a lower ground that is an area excluding the lower clearance area of the lower surface of the circuit board and overlaps the upper ground are defined on the lower 20 surface of the circuit board.

17. The multi-band antenna module of claim 1, wherein the first side surface of the circuit board is orthogonal to the second side surface of the circuit board, and the first conductor area is parallel to the first side surface 25 of the circuit board, and the second conductor area is parallel to the second side surface of the circuit board.
